Frank B. Pastir ^{Inventor}

By *Wm. S. Dodge* ^{Attorney}

UNITED STATES PATENT OFFICE.

FRANK B. PASTIR, OF BARBERTON, OHIO.

DESIGN FOR A TOY BALLOON.

59,864.

Specification for Design.

Patented Nov. 29, 1921.

Application filed July 9, 1921. Serial No. 483,569. Term of patent 14 years.

To all whom it may concern:

Be it known that I, FRANK B. PASTIR, a citizen of Czecho-Slovakia, residing at Barberton, in the county of Summit and State of Ohio, have invented a new, original, and ornamental Design for Toy Balloons, of which the following is a specification.

In the accompanying drawing, the figure

is a perspective view illustrating a toy balloon embodying the invention.

I claim:—

The ornamental design for a toy balloon, as shown.

In testimony whereof I have hereunto set my hand.

FRANK B. PASTIR.
